UNITED STATES PATENT OFFICE.

EDDY T. THOMAS, OF NEW YORK, N. Y., ASSIGNOR TO THE GOLD MEDAL SEWING MACHINE COMPANY, OF ORANGE, MASSACHUSETTS.

SEWING-MACHINE.

SPECIFICATION forming part of Letters Patent No. 243,326, dated June 21, 1881.

Application filed January 24, 1881. (No model.)

To all whom it may concern:

Be it known that I, EDDY T. THOMAS, of New York, county of New York, and State of New York, have invented Improvements in Sewing-
5 Machines, of which the following description, in connection with the accompanying drawings, is a specification.

This invention relates to improvements in sewing-machines of that class employing an 10 eye-pointed needle and shuttle and making the lock or shuttle stitch; and my invention has for its object to simplify the construction of the same, as will be hereinafter described.

My invention consists in the combination, 15 with the rotary needle-bar-actuating shaft in the overhanging arm, eccentric thereon, and rack-bar actuated by the said eccentric, of a rocker-shaft and a pinion thereon engaged by the said rack-bar, and a shuttle-carrier secured 20 to the said rocker-shaft. I make this same rocker-shaft which vibrates the shuttle-carrier the means for imparting movement to the four-motioned feed-bar, by providing it with a cam which raises the said feed-bar and permits it 25 to fall, while a lateral pin or projection on the said cam, working on a forked lever having an adjustable fulcrum, imparts to the feed-bar its backward and forward movement.

Figure 1 represents, in side elevation and 30 partial section, a sufficient portion of a sewing-machine to illustrate my invention. Fig. 2 is a section of Fig. 1 on the dotted lines xx . Fig. 3 is a section on the dotted line x^2x^2 , Fig. 1, to show the feeding mechanism. Fig. 4 is a detail of the feed-bar. Fig. 5 is a detail of the shuttle-carrier and its connected parts, and 35 Fig. 6 is a modification representing a different form of rack-bar.

The frame-work a , overhanging arm a' , rotating shaft a^2 therein, and crank-pin a^3 , which is to enter the so-called "heart-shaped" groove in a plate connected, as usual, with the needle-bar, but not shown, are supposed to be the same as in the well-known "New Home" sewing-machine. The shaft a^2 has upon it an eccentric, 45 b , which actuates the rack-bar b^2 , the teeth of which engage the pinion b^3 on the shuttle-carrier rock-shaft b^4 and impart to the said shaft a rotary reciprocating movement, causing the 50 shuttle-carrier c , provided with suitable horns, to carry the shuttle through the loop, which will

be formed in the usual manner on the needle-thread. The face of the shuttle will be kept pressed up against the face of the shuttle-race 2, and down on the carrier by the carrier-spring 55 c' . The shuttle (not shown in the drawings, to avoid confusion of lines) will be of usual construction.

The shaft b^4 has connected with it a cam, d , of proper shape to lift the feed-bar e at the 60 proper time to engage the material to be fed along under the usual presser-foot and needle, (not shown,) and to permit the said feed-bar to fall at the proper time under the pressure of the spring 3. At its front side this cam d has 65 extended laterally from it a stud or projection, d^2 , (see Fig. 3,) which at proper times during the movements of the rocking-shaft b^4 acts upon one or the other of the two legs of the forked feed-moving lever g , pivoted at its upper end, 70 as at k , to the feed-bar e . This forked lever is slotted, as shown in Fig. 4, to surround the fulcrum 4 on the movable fulcrum-bar h , pivoted at one end, at 5, to a lug, 6, of the frame-work, while its other end is suitably slotted, so that 75 it may be adjusted and held in adjusted position by the set-screw i . Elevation or depression of the said fulcrum-bar will vary the position of the fulcrum 4, and consequently change the throw of the lever g and feed-bar. 80

In connection with the feed-bar I have shown a back-stop, l , which regulates the backward movement of the feed, and consequently the length of the stitch, the lug m of the feed-bar striking against the said stop. This back-stop 85 is of usual construction, and, as herein shown, is the forward end of the pivoted lever n .

In Fig. 6, I have shown the rack-bar arranged to vibrate about the center o , instead of to reciprocate, as in Fig. 2. The rack-bar in Fig. 90 2 is kept in engagement with the teeth of the pinion by means of the arm p , which bears against the right-hand side of shaft b^4 , while the rack and pinion engage on the left-hand side.

I claim—

1. In a sewing-machine for making a lock or shuttle stitch, the frame-work, rotating needle-bar-actuating shaft, eccentric thereon, and vertically-reciprocating rack-bar provided with 100 the arm p and actuated from the said eccentric, combined with the rocker-shaft b^4 , its pinion b^3 ,

and vibrating shuttle-carrier connected therewith, substantially as described.

2. The frame-work, rotating needle-bar-actuating shaft, and eccentric thereon, the rack-bar actuated thereby, and the rocker-shaft b^4 , its pinion b^3 , and vibrating shuttle-carrier c , connected therewith, combined with the feed-cam d , the stud d^2 thereon, feed-bar e , forked feed-moving lever pivoted thereon, and the adjustable fulcrum therefor, substantially as described.

3. The rocker-shaft b^4 , cam d and its stud

d^2 , and feed-bar and forked feed-moving lever pivoted thereon, combined with the movable bar h and fulcrum 4 for the said feed-moving lever, to operate as and for the purpose described. 15

In testimony whereof I have signed my name to this specification in the presence of two subscribing witnesses.

EDDY TAYLOR THOMAS.
